 New York, N. Y., a corporation of New York

Application February 12, 1938, Serial No. 190,246

7 Claims. (Cl. 178—27)

This invention relates to communication systems and more particularly to synchronously operated systems, one well known type of which is the printing telegraph system.

5 One of the objects of the present invention resides in the provision of a synchronous system in which a predetermined number of impulses, namely three, is employed to represent all characters to be transmitted and received.

10 Another object of the present invention resides in the provision of a synchronous system in which different characteristics are imparted to the impulses, thereby increasing the number of character permutations and effecting the selection of 15 a single circuit for each permutation for a plurality of selection circuits at the receiver.

Another object of the invention resides in the provision of control means at the receiver which is conditioned by the first of a plurality of impulses representing a character to control selection means, the latter in turn being partially conditioned by the second impulse and completed by the third impulse at a differential time in the cycle, to effect the completion of a single character selection circuit.

25 Still another object resides in the provision of a synchronous system in which control members are used to initiate impulses at the transmitter, a predetermined number of these, namely three, being operated for each character to be transmitted, and a common control member being operated simultaneously, regardless of the character to be transmitted, to initiate a control impulse to effect the engagement of the normally 30 latched members of a rotary distributing means with its synchronously driven members so as to condition a predetermined number of control circuits for transmitting the character impulses.

35 Various other objects and advantages of the invention will become obvious from the following description of one form of mechanism embodying the invention or from an inspection of the accompanying drawings; and the invention also constitutes certain new and useful features of 40 construction and combination of parts herein-after set forth and claimed.

In the drawings:

Fig. 1 shows, in part one type of transmitting and receiving control unit.

50 Fig. 2 is a detail perspective of an operating mechanism of the unit shown in Fig. 1.

Fig. 3 shows a rotary distributor means with one type of clutching arrangement which may be employed at the transmitter.

55 Fig. 4 is a circuit diagram for the transmitting station.

Fig. 5 is a circuit diagram for the receiving station.

For illustrative purposes, this invention is 60 shown as embodying a well known type of record-

ing unit, which may be similar in construction to the Electromatic typewriter, shown and described in detail in U. S. Patent No. 1,777,055, and hence requires only the following brief description.

5 Referring to the drawings and particularly to Fig. 1, well known means are provided for actuating the type bars 16, comprising a constantly rotating roller 10, cooperating with a series of individual power units each comprising a cam 11, the engagement of the cams being controlled selectively by the character key bars 17.

10 Any suitable means may be provided to rotate the power roller, in the direction indicated by the arrow, which is adapted to cooperate with two rows of cam units arranged in the front and rear of the roller. The cam 11 may be provided to be pivoted on one arm of a bell crank lever 12 which is pivoted in the frame of the recording unit, as indicated generally by reference character 13, the other arm of the said bell crank lever being operatively connected with an arm of bell crank lever 14 by means of link 15. Another arm of 15 said lever 14 is connected to the type bars 16 in a well known manner, so as to effect operation 20 of the type bars or any other suitable means connected to the bell crank levers upon selective operation of the controlling key bars 17.

25 The pivoted bell crank lever 12 is operated by the associated cam 11 whenever the latter engages the driven roller; the engagement of the cam with the roller is controlled by means of the associated control key bar 17 in a manner which will now be briefly described.

30 Referring now to Fig. 2, the cams occupy normally the positions as shown in this figure, which represents one of the rear bank of units. In this position the impeller-arm 18 is urged, by the associated coil spring 19, against one of the impeller lugs 20, which at the time is in the lower 35 position, and tends to turn the cam 11 in a clockwise direction. This is prevented, however, by the engagement of one of the detents 21 on the cam, with the upper stop leg 22 on stop lever 23. If, however, the corresponding key bar is operated, the bifurcated lower end (Fig. 1) of extension arm 24 associated with one of the said key bars 17 engages an arm 25 at the upper end of the stop lever 23 which extends laterally through an opening in the bell crank lever 12. The arm 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 until the high point has been reached and passed. This causes the whole cam unit to swing around the pivot 13 so as to pull down the corresponding link and actuate one of the type bars or any other mechanism with which the cam unit may be connected.

After the high point of the cam is passed the cam loses contact with the roller, but the said impeller-arm 18 tends to continue the rotation thereof by engaging the second impeller-lug 29 of cam 11 until the second detent 27 engages one of the stop lugs. Since the half rotation of the cam consumes only a small fraction of a second, it is difficult to release the key bar within this short interval, so that it is the lower lug 28 which is first engaged, but upon the release of the key bar and the return of the stop lever 23 to normal position, this lug 28 disengages the detent, whereupon the impeller-arm rotates the cam slightly, 20 and the said detent then engages the upper stop lug 22.

It is obvious then that depression of a key bar releases the revolubly mounted cam to engage and be actuated by the power roller in turn operating the associated bell crank lever and its attached links to cause the associated mechanism such as the type bars and other operating mechanisms, to be operated. It is to be understood that an individual cam unit is provided for each 30 type bar or other functional mechanisms associated therewith.

The action of the cam mechanism has been described with respect to one of the rear bank of cam units; in the case of those of the forward bank the operation is analogous, but the direction of movement, and the order of operation of the stop lugs, is reversed. For example, if the bifurcated arm 24a is positioned to engage the arm 25a at the upper end of stop lever 23a 35 by virtue of operation of the associated key bar, the said arm is positioned rearwardly or to the left as viewed in Fig. 1, and the lower end of the stop lever 23a is moved forwardly, that is, to the right as viewed in said figure. This said operation is effective to release the cam, by virtue of positioning the lower stop lug 28a out of the path of detent 21a, thus permitting the spring urged impeller arm 18a to rotate the cam slightly in a clockwise direction to effect engagement of 40 the lower lobe of cam 11 and the power roller. Upon completion of a half revolution of the cam 11, the second detent 27a engages first in the upper stop lug 22a while the stop lever 23a is in an operated position, but upon release of the 45 said associated key bar and the return of the said stop lever to normal position, this lug 22a disengages the said detent and the impeller-arm rotates the cam slightly so that the said detent then engages the lower stop lug 28a, as shown 50 in the figure. In this manner the bell crank lever 12a is rotated about the pivot 13a to operate the associated type bar or any other mechanism associated therewith. For further structural details of the cam units, reference should be made 55 to the above mentioned patent.

When the mechanism described above is used as a transmitter, the cam 11, when released, is arranged to operate a plurality of control members such as the contacts generally designated 10. 70 An assembly of these contacts is located in the path of each of the cams, so that the depression of any key bar 17 will result not only in the actuation of a type bar 16 but also in the closing of a corresponding contact assembly for a very brief interval of time. The closing of these contacts

effect the initiation of impulses to represent the character to be transmitted.

When the mechanism described above is used as a receiver, a solenoid 30 is associated with each key bar 17 so that upon energization of the solenoid the key bar will be drawn down and cause the corresponding type bar 16 to be actuated for the purpose of recording the character received. Obviously, the operation of the mechanism resulting from the energization of the solenoid 30 10 will be the same as that resulting from the manual depression of the key bar 17.

In the present system, rotary distributor units are located at the transmitting and receiving stations and are driven in synchronism by synchronous motors or other suitable means well known in the art. One type of rotary distributor unit, generally designated 40 (Fig. 3), is shown to comprise two commutators and two control rings each having brushes associated therewith. 15

The commutators, designated 41 and 42, are identical in every respect and are electrically insulated from each other by any suitable means. Commutator brushes 43 and 44 are mounted on an arm 45 and are insulated from each other and the arm by insulating material such as 46. The brush arm 45 is fixed to a constantly rotating shaft 47 which is driven by a synchronous motor (not shown). Thus the commutator brushes are caused to rotate continuously around the peripheries of the commutators 41 and 42 25 and engage successively the individual conductive segments 41-1 to 6 and 42-1 to 6 respectively in a manner well known in the art.

The control rings, designated 48 and 49, are also electrically insulated from each other and are provided with insulating segments 50 and 51 respectively, the purpose of which will be described later in connection with the electrical circuits of the system. Two pairs of insulated brushes 52 and 40 53 are mounted on a brush arm 54 and are associated with control rings 48 and 49 respectively. The brush arm 54 is associated with a clutching arrangement, and is thereby held in a latched position except when the clutch coil 55 is energized by a control impulse automatically sent to it simultaneously with the initiation of character impulses to be transmitted. This feature will be explained in detail later in connection with the electrical circuit diagram of the transmitting station. Upon momentary energization of the clutch coil 55 an arm 56 is displaced to the left and allows a dog 57 to be released and, under the impetus of spring 58, the dog will bear on the surface of a clutch member 59 pinned to the continually running shaft 47 until a predetermined time, near the end of the rotary distributor cycle in which the clutch coil was energized, when the dog 57 will engage in a single tooth 60 of the clutch member. Once engaged with the clutch member, the dog will remain engaged and drive its connected mechanism through one cycle of operation, at end of which it will latch up on latching point 61 of arm 56. The dog 57 is connected by means of a collar 62 to the control 50 ring brush arm 54 and consequently with each engagement of the dog in the clutch member 59, the control ring brushes will be rotated through one complete cycle around the periphery of control rings. This operation is repeated for each 55 character to be transmitted.

At the receiving station, a rotary distributor unit similar to that at the transmitter is employed with the exception that no clutching arrangement is provided, and the receiving con- 75

trol ring brushes are caused to rotate continuously in synchronism with the receiving commutator brushes by having the controlling brush arm as well as the commutator brush arm fixed 5 to the continuously rotating shaft. The purpose of the control ring clutch employed at the transmitter was to hold the control ring brushes latched up so that brushes 52 would rest on the insulated portion 50 of control ring 48 to prevent 10 the sending of stray impulses over the line due to commutator brushes 43 and 44 continuously traversing the commutator segments. How this accomplishes its purpose will become apparent from the circuit diagram (Fig. 4) and 15 the description to follow. It is evident that if these stray impulses are prevented from getting out to the line from the transmitter, there should be none to guard against at the receiver, so that 20 a receiver control ring clutch in this system is not necessary.

A circuit diagram which may be used at the transmitting station is shown in Fig. 4 and will now be described with reference to that figure. As has been previously explained, a plurality of 25 control members such as contacts 70 (Fig. 3) are operated for each character to be transmitted but only four such control member groups (70, 71, 72 and 73) are shown in Fig. 4, that being considered representative of the entire transmitter 30 circuit for purposes of explanation. Impulses initiated from the operation of a control member group are stored up and controlled by means of twelve relays designated as R-1 to R-12 inclusive. These relays are of the double-wound 35 coil type, each having an energizing coil and a holding coil.

Assumed, for example, that "A" is the character to be transmitted. When the character key bar for the character "A" is depressed, contacts 40 70 are closed for a brief interval of time as previously described, and four circuits are completed. A circuit is established from ground 80, contact 70a now closed, conductor 81, clutch coil 55, to grounded battery 82, thus energizing the clutch 45 coil. At the same time circuits are completed to energize relays R-1, R-3, and R-10. The R-1 relay is energized by a circuit from contact 70b through conductors 83 and 84, R-1 relay coil, and via common conductor 85 to grounded 50 battery 82. The R-3 relay is picked up by a parallel circuit from contact 70C, via conductors 86 and 87 to the R-3 coil, common conductor 85 to grounded battery 82. Another parallel circuit energizes the R-10 relay as follows: contact 70d, 55 conductors 88 and 89, R-10 coil, common conductor 85, to grounded battery 82. These relays are each provided with three contacts designated generally as 90, 91 and 92, which close when the coils of these relays are energized. Contacts 90 60 of relays R-1, R-3 and R-10 close to provide holding circuits for the coils of these relays as follows: grounded battery 82, common conductor 85, coils of relays R-1, R-3 and R-10, contacts 90 of these relays, conductor 93, brushes 53 on control ring 49 to ground 94. This circuit holds 65 relays R-1, R-3 and R-10 energized until a point after the signals have been sent to the line when brushes 53 pass on the insulated portion 51 of their associated ring 49.

70 Contacts 91 and 92 of the above relays also close upon energization of these relays to prepare circuits between a direct current source of potential such as battery 95 and transmitter commutator segments 41-1, 41-3, and 42-2. These 75 circuits are allowed to be completed when

brushes 52 pass off the insulated portion 50 and on to the conducting portion of their associated ring 48. The polarity of the outgoing impulses will be plus on brush 43 and minus on brush 44 from segments 1 and 3, and minus on brush 43 5 and plus on brush 44 from segment 4. The circuits connecting battery 95 with commutator segments for impressing these polarities is as follows: Positive side of battery 95, conductor 96, contacts 91 of relays R-1 and R-3, to 10 commutator segments 41-1 and 41-3 respectively; and from negative side of battery 95, conductor 97, brushes 52 now on metallic portion of ring 48, conductor 98, contacts 92 of the R-1 and R-3 relays, to commutator segments 42-1 15 and 42-3 respectively. Also, for the impulse through the R-10 relay, the circuit runs from the positive side of battery 95, conductor 96, contacts 91 of the R-10 relay via conductors 98a and 99 to commutator segment 42-2; and 20 from negative side of battery 95, conductor 97, brushes 52, ring 48, via conductor 98 to contacts 92 of the R-10 relay, conductors 100 and 101, to commutator segment 41-4. Impulses are sent over the line from the segments upon which the 25 potentials were impressed as brushes 43 and 44 pass over these segments.

A circuit diagram suitable for use at the receiver is shown in Fig. 5. With this circuit arrangement a total selection of 48 characters is possible from 30 permutations of three impulses representing each character. The selection is effected by the use of relays, each with an energizing coil and a holding coil, a rotary distributor unit similar to that used at the transmitter without the clutch attachment, a polarity distinguishing means for the incoming impulses such as polarized relay 110 35 (Fig. 5), a plurality of control and selection circuits, and a solenoid for each of the character keys. Assuming a synchronous system, commutator brushes 111 and 112 will be rotating correspondingly to brushes 41 and 42 of the transmitter, segment for segment. Also receiver control ring brushes 113 and 114 will be rotating 40 continuously in fixed relation with brushes 111 and 112 as has been previously explained. 45

In receiving the character A, to continue with the above example, the first impulse received is the impulse from transmitter segment 41-1. This impulse was negative to the line leading 50 from brush 44 and positive to the line leading from brush 43 at the transmitter. Consequently, at the receiver, polarized relay 110 is caused to be energized and shift its armature 107 to the left closing contacts 108 and passing current through brush 111 to segment 115-1, conductor 117, R-13, conductor 118 to the other side of the line, thus picking up the R-13 relay. A holding circuit for this relay is established through its contacts 119 from grounded battery 120, via conductors 121 to R-13 coil, contacts 119 now closed, via conductor 122 to brushes 114 on metallic portion of receiver control ring 124 to ground 125. Multiple contacts 126 associated with relay R-13 close, connecting relays R-17 65 to R-20 and R-24 to R-27 inclusive to segments 3, 4, 5, and 6 of the receiving commutators 115 and 116 respectively. The next impulse will be of the same polarity as the first and will come through brush 111 to commutator segment 115-3, 70 then via conductor 127 through contacts 126A now closed, R-17 coil, via conductors 128 and 118 to the other side of the line. The contacts 129 of relay R-17 close, and a holding circuit similar to that for the R-13 relay is established from 75

grounded battery 120, via conductors 130 and 131 to R-17 coil, contacts 129 now closed, via conductor 122 to brushes 114 on metallic portion of ring 114, to ground 125.

5 With the energization of relay R-17, contacts 133 also close to connect one side of six character key solenoids (A, B, C, D, E and F) to one side of brushes 113 which at this time are still on insulated portion 132 of ring 123. Consequently no circuit is as yet completed to one side of these solenoids from grounded battery 120.

The third impulse to be received in the permutation representing the character A will be of opposite polarity to the first two impulses. Polarized relay 110 will shift its armature 107 to the right, closing contacts 109, and current will pass through brush 112, commutator segment 116-4, then via conductor 134 through contacts 126f to the R-25 coil, conductors 135 and 118, to the other side of the line. Contacts 136 close to establish a holding circuit for relay R-25 from grounded battery 120, via conductor 121 to the R-25 coil, contacts 136, conductor 122, brushes 114 now on conducting portion of ring 124, to ground 125.

The energization of relay R-25 causes the multiple contacts 137 associated with it to close and thereby connect one side of six solenoids (A, N, T, Y, U and BS) to ground 138. A battery circuit is now prepared through the coil of the A solenoid and will be completed when brushes 113 pass onto the metallic portion of ring 123. The circuit is as follows: grounded battery 120, via conductor 139 to brushes 113 on metallic portion of ring 123, conductor 140, contacts 133, solenoid A, contacts 137 now closed, conductor 141, to ground 138. The solenoid A is thus energized and is adapted to operate a suitable recording means such as has already been described. Immediately upon the completion of the recording portion of the cycle, the holding circuits for all relays are broken by the receiver control ring brushes passing onto the insulating portion of their respective control rings.

45 For any other character to be communicated, the operation of the circuits is similar and can be easily followed from the above description of the circuit operation for the character A. An example of the code which may be used in combining the impulses into permutations representing characters is given in the table below with polarities on each segment of transmitting commutator 42 on which the impulses are to be impressed.

	Segments					
	42-1	42-2	42-3	42-4	42-5	42-6
A	-		-	+		
N	-		-	+		
D	+		-	+	-	
Y		+	-	+		
U		+	-	-		+

65 A synchronizing segment S is placed between segments 2 and 3 on commutators at the transmitting and receiving stations in order to give more time for the relays called by the impulses from segments 2 to operate, as they must do before subsequent circuits can be set up by being closed to the commutator. A synchronizing impulse is sent through every cycle on the S segment, and may be arranged to operate step mechanism if the commutators at the receiving station get out of synchronism with the trans-

mitting commutators. This method is so well known in the art that further description is believed unnecessary.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. A communication system comprising, in combination, rotary distributor means to receive a plurality of plus and minus impulses representing a character, polarity differentiating means to direct the impulses to the distributor means in accordance with the first impulse reality of control circuits and character selection circuits, means under control of the distributor means in accordance with the first impulse received to condition a predetermined number of said control circuits, means also controlled by 25 the distributor means operating through one of the conditioned control circuits in accordance with the second impulse received to condition a predetermined number of said character selection circuits, and further means controlled by said distributor means operating through another of the conditioned control circuits to effect the completion of a single one of the conditioned selection circuits to select the character represented by said impulses.

2. A communication system comprising, in combination, means to receive a plurality of impulses comprising rotary distributor means provided with a plurality of segments, control means cooperating with a predetermined number of 40 said segments and arranged to be selectively operated in accordance with the first impulse received by said distributor means, a plurality of groups of control circuits cooperating with the remaining segments, one group of said control circuits 45 being conditioned in accordance with the operated control means, a plurality of groups of selection circuits, means rendered operative upon reception of the second impulse from one of said remaining segments through its related control 50 circuit within the conditioned group to prepare a set of said selection circuits, and means rendered operative upon reception of the second impulse through one of said conditioned control circuits related to another of said remaining 55 segments to prepare another set of selection circuits, thereby completing a single selection circuit which is common to both sets of selection circuits.

3. A synchronous communication system comprising, in combination at the transmitter, rotary distributor means including normally inoperative transmission control rings and a constantly rotating commutator, a plurality of control circuits, key-controlled means for selecting a predetermined number of said control circuits for operation in accordance with the depression of a character key, further means controlled by the key at the same time for energizing another of said control circuits, clutching mechanism including 65 a clutch magnet operated upon energization of the last-mentioned circuit to cause the transmission control rings to rotate with the commutator in a predetermined relation to bring the selected control circuits under the control of 75

CERTIFICATE OF CORRECTION.

Patent No. 2,181,989.

December 5, 1939.

CHARLES R. DOTY.

It is hereby certified that error appears in the printed specification of the above numbered patent requiring correction as follows: Page 4, second column, lines 20 and 21, claim 1, for "the first impulse reality" read their polarities, a plurality; and that the said Letters Patent should be read with this correction therein that the same may conform to the record of the case in the Patent Office.

Signed and sealed this 2nd day of April, A. D. 1940.

Henry Van Arsdale,

(Seal) Acting Commissioner of Patents.
